UNITED STATES PATENT OFFICE.

OTTO HONZ, OF SCHENECTADY, NEW YORK, ASSIGNEE TO GENERAL ELECTRIC COMPANY, A CORPORATION OF NEW YORK.

ASYMMETRICAL VAPOR-CONDUCTING MEDIUM FOR ALTERNATING CURRENTS.

1. 119,600.

Specification of Letters Patent.

Patented Dec. 1, 1914.

Application filed March 23, 1909. Serial No. 143,873.

To all whom it may concern:

Be it known that I, Otto Honz, a citizen of the United States, residing at Schenectady, county of Schenectady, and State of New York, have invented certain new and useful Improvements in Asymmetrical Vapor-Conducting Mediums for Alternating Currents, of which the following is a specification.

10 My invention relates to the transmission of alternating currents through a vapor.

A vapor rectifier tube conductive for waves of a given direction only and so operating as a rectifier is constructed in accordance with my invention so as to avoid arcing between the anodes.

15 I may utilize my invention to obtain a direct current from an alternating current source, in which case the energy is utilized elsewhere than in the vapor conducting medium, or I may convert the energy derived from the source exclusively into light, in which case the principal consumption of energy takes place in the conducting-medium itself.

20 In carrying my invention into practice I make use of a highly exhausted receptacle provided for example with multiphase electrodes, one at least of which is of vaporizable material. From the vaporizable material in the envelop, and through the instrumentality of means independent of the multiphase source, I generate ionized vapor in the envelop. By the term ionized vapor I 25 mean vapor which is produced electrically and which is then electrically conducting. By reason of the presence of this ionized vapor, current flow, from the multiphase source, is initiated in the envelop and maintained stable.

30 The novel features which characterize my invention are pointed out in the appended claims. The invention itself however will be best understood by reference to the following description taken in connection with the accompanying drawings in which—

Figure 1 represents one embodiment of my invention and Fig. 2 another embodiment.

35 In Fig. 1, an exhausted envelop or receptacle, of glass or other suitable material,

is indicated at 1. In the present instance this envelop is provided with upright tubular extensions 2, 3, 4 and 5, in which are located electrodes or anodes 6, 7, 8 and 9 respectively. At the bottom of the envelop are formed cups which contain bodies of mercury 10 and 11 which also serve as electrodes. The upper electrodes 6, 7, 8 and 9 are preferably formed of some non-vaporizable material such as artificial graphite, iron or the like and are connected respectively to multiphase supply leads which in the present instance extend from the terminals of two transformer secondaries 12 and 13. Through these connections alternating differences of potential are impressed on these electrodes. The location of these electrodes or anodes in the tubular chambers or extensions so that in a direct line between them there intervenes a portion or portions of the container or glass envelop has the important advantage of preventing or reducing arcing between the anodes due to the alternating differences of potential between them. The primaries 14 and 15, corresponding to the two secondaries 12 and 13, are supplied with current from a suitable two-phase source. The lower electrode 10 is connected to a consumption circuit containing translating devices of any desired character such for example as a storage battery 16, lights 17 and a motor 18. The other lead of this consumption circuit is connected to a conductor 19 joining together the middle points of the secondaries 12 and 13.

40 A source of direct current such as a small storage battery 20 is electrically connected to the two electrodes 10 and 11. This battery serves to produce and maintain an arc in the envelop between the electrodes 10 and 11. This arc may be started by causing the bodies of mercury 10 and 11 to come into momentary contact with each other. As the mercury separates, the short circuit previously formed is broken, thus springing the arc. This result may be accomplished by shaking the envelop so as to cause the mercury to flow over the bridge or barrier 21 separating the two bodies of mercury, so that as the mercury flows back into the position of equilibrium, the circuit thus formed

separates across the barrier or wall 21 thus forming the arc desired. As soon as this arc is formed, the generation of ions, or ionized vapor, renders the interior of the envelop conductive for currents of one direction, thereby enabling current to flow from the upper electrodes or anodes in the envelop to the common electrode 10. This current flow is always unidirectional, but owing to the multiphase character of the source, current flows in succession from the upper electrodes to the lower or common electrode 10 so that there is no time during which there is a complete cessation of current flow from the alternating current source. The secondaries 12 and 13, in which currents are generated 90° apart in phase, really constitute sources of four-phase alternating current. The resulting unidirectional current which flows through the envelop 1 and thence to the translating devices is therefore nearly steady in character. Such slight fluctuations as may exist may be smoothed out by means of an inductance coil as at 22. In performing this function the inductance coil causes each current wave to lag behind its electro-motive force, whereby the current from each phase of the supply system, instead of passing through zero periodically, is always flowing at the instant the electro-motive force passes through zero.

In Fig. 2 I have represented the application of my invention to a source of six-phase current. The exhausted envelop or receptacle for the vapor conducting-medium is indicated at 23. This envelop may be of glass or other suitable material. It is somewhat pear shaped and is provided with electrodes 24 to 29 inclusive located in the dome-like portion of the envelop as indicated. Suitable leading-in wires serve to make electrical connection with these electrodes and are connected respectively with the terminals of three transformer secondaries 30, 31 and 32, the primaries of which are indicated at 33, 34 and 35. These primaries are supplied with three phase current from any suitable source.

A pocket or cup in the lower portion of the receptacle 23 is filled with a body of mercury 36 constituting a common cathode co-operating with the upper electrodes or anodes. This cathode is connected to a circuit including translating devices such for example as a storage battery 37, lamps 38 or a motor 39. Current after passing through the translating devices returns through a return conductor 40 connected to the middle points of the three secondaries 30, 31 and 32. Due to this middle connection, the three secondaries impress six-phase electromotive forces upon the upper electrodes in the receptacle 23, as will be readily understood by one skilled in the art.

An auxiliary mercury electrode 41 serves, like the auxiliary electrode 11 in Fig. 1, to generate and maintain an auxiliary arc in the receptacle by means of energy supplied by a small storage battery 42 or other source of direct current. This auxiliary arc is started in the same manner as the auxiliary arc described in connection with Fig. 1, and when started renders the interior of the envelop 23 conductive for current waves of one direction. The result is a flow of current waves from the upper electrodes 24 to 29 inclusive, taking place from one electrode and then from another in continuous succession. These waves, which are of one direction, are displaced from each other in six-phase relation, in correspondence with the six-phase relation of the impressed electromotive forces, and result in a substantially uniform current passing to the translating devices.

Though in both figures of the drawings I have illustrated my invention as applied to the rectification of alternating current, it is to be understood that the translating devices may be omitted and the energy derived from the source utilized entirely in the envelop for the purpose of producing light. Also, though I have observed that the auxiliary starting arc may be kept in continuous operation in order to render the action of the apparatus more stable, it may be used for starting purposes only and discontinued after the apparatus is started up through its instrumentality.

What I claim as new, and desire to secure by Letters Patent of the United States, is:

1. In a vapor electric apparatus, the combination of an exhausted envelop having a plurality of upright tubular extensions, solid electrodes located in said tubular extensions and maintained at different polarities, and a co-operating vaporizable electrode.
2. The combination of an exhausted envelop having a plurality of upright tubular extensions, an anode in each extension, and means for maintaining an alternating difference of potential between said anodes.
3. The combination of an exhausted envelop having a plurality of upright tubular anode chambers, anodes in said chambers, a vaporizable cathode, and a source of alternating electromotive force connected to said anodes.
4. The combination of an evacuated envelop having a plurality of extensions each closed at one end, a solid anode in each extension, a vaporizable cathode, and means for producing an alternating difference of potential between said anodes.
5. The combination of an exhausted envelop having a plurality of anode chambers the openings into which are out of line with each other, anodes in said chambers, a co-

- 5 operating vaporizable cathode, and means 65 for maintaining an alternating difference of potential between said anodes.
6. A rectifier tube consisting of an exhausted envelop having a plurality of anode 70 chambers, solid anodes alternating in potential in said chambers so located that a portion of the envelop intervenes, and a co-operating vaporizable cathode.
- 10 7. A rectifier tube having a plurality of solid anodes alternating in potential and a co-operating cathode, the tube being shaped so that a portion or portions thereof are interposed between the anodes.
8. A rectifier tube having a plurality of solid anodes alternating in potential, and a co-operating cathode, and chambers for the respective anodes, the openings into which are out of line with each other.
- 20 9. The combination with a source of alternating current, of a highly exhausted envelop provided at its lower portion with a vaporizable electrode and having a plurality of arms, solid electrodes located respectively 75 in said arms above the level of said mercury electrode and connections between said solid electrodes and said source.
10. The combination of an exhausted envelop having a cathode and a plurality of solid anodes, the anodes alternating in potential and having a wall or portion of said envelop interposed in a direct line between them.
- 30 11. In a vapor electric apparatus, the combination of an exhausted envelop having a plurality of upright tubular extensions, electrodes located in said tubular extensions and maintained at different polarities, and a co-operating vaporizable electrode.
- 40 12. The combination of an evacuated envelop having a plurality of extensions each closed at one end, an anode in each extension, a vaporizable cathode, and means for producing an alternating difference of potential between said anodes.
13. A rectifier tube consisting of an exhausted envelop having a plurality of anode 85 chambers, anodes alternating in potential in said chambers so located that a portion of the envelop intervenes, and a co-operating vaporizable cathode.
- 50 14. A rectifier tube consisting of an exhausted envelop having a plurality of anodes alternating in potential so located that a portion 90 of the envelop intervenes, and a co-operating vaporizable cathode.
15. A rectifier tube having a plurality of anodes alternating in potential and a co-operating cathode, the tube being shaped so that a portion or portions thereof are interposed between the anodes.
- 60 16. The combination with a source of alternating current, of a highly exhausted envelop provided at its lower portion with a vaporizable electrode and having a plurality of arms, electrodes located respectively in said arms above the level of said mercury electrode and connections between said solid electrodes and said source.
17. The combination of an exhausted envelop having a cathode and a plurality of anodes, the anodes alternating in potential and having a wall or portion of said envelop interposed in a direct line between them.
- 75 18. In a vapor electric apparatus, the combination with a source of alternating current, of an exhausted container, an electrode impressed with a positive potential, another electrode impressed with a negative potential, said last named electrode being located in a tubular portion of said container and being shielded from said first named electrode.
- 80 19. In a system of electrical distribution in combination with an exhausted container and suitable electrodes therein, at least one of which is vaporizable, of means for impressing alternating potentials upon the electrodes together with separate chambers containing the said electrodes, said chambers forming a part of the container and being so disposed as to shield one electrode from mercury particles and electric charges occurring in the other electrode.
- 85 20. A vacuum rectifier including a hermetically sealed and completely exhausted container, a vaporizable reconstructing liquid cathode therefor located in a suitable pocket at the bottom of said container and a plurality of upwardly extending branching tubular chambers in said container, each chamber inclosing a solid anode.
- 90 21. A vacuum rectifier including a hermetically sealed and completely exhausted container, a vaporizable reconstructing liquid cathode therefor located in a suitable pocket at the bottom of said container and a plurality of upwardly extending branching tubular chambers in said container, each chamber inclosing a solid anode located at the remote end thereof.
- 100 22. A vapor rectifier comprising a hermetically sealed and completely exhausted container, a bulbular portion of said container, relatively long tubular extensions extending sidewise and upwardly on opposite sides of said bulbular portion and a vaporizable reconstructing cathode at the bottom of said bulbular portion, together with solid anodes located at the extreme ends of the said tubular portions.
- 105 23. The combination of an exhausted envelop having a plurality of anode chambers, anodes in said chambers, the openings into the chambers being out of a line connecting the anodes, a co-operating vaporizable cathode, and means for maintaining an al-

ternating difference of potential between said anodes.

24. A rectifier tube having a plurality of anodes alternating in potential, and a coöperating cathode, and chambers for the respective anodes the openings into which are out of line with each other.

25. A rectifier tube having a plurality of anodes alternating in potential, and a co-

operating cathode, and chambers for the respective anodes the openings into which are out of a line connecting the anodes.

In witness whereof, I have hereunto set my hand this 20th day of March, 1903.

OTTO HOLZ.
